UNITED STATES PATENT OFFICE

169,264

DISPENSER OF ALIMENTS OR CONDIMENTS
OR SIMILAR ARTICLEIsadore Lapofsky, Hillside Township, Essex
County, N. J.

Application February 9, 1953, Serial No. 23,483

Term of patent 14 years

(Cl. D58—8)

To all whom it may concern:

Be it known that I, Isadore Lapofsky, a citizen of the United States, residing in the township of Hillside, county of Essex, and State of New Jersey, have invented a new, original, and ornamental Design for a Dispenser of Aliments or Condiments or Similar Article, of which the following is a specification, reference being had to the accompanying drawings, forming a part hereof.

Figure 1 is a front elevational view of a dispenser of aliments or condiments or similar article, showing my new design;

I claim:

The ornamental design for a dispenser of aliments or condiments or similar article, as shown.

ISADORE LAPOFSKY.
